FACE SHIELD

William F. Serr, New York, N. Y., assignor to
Eric Pusinelli, New York, N. Y.

Application January 26, 1940, Serial No. 315,630
In Great Britain April 22, 1939

2 Claims. (Cl. 2—10)

This invention relates to face shields, such as eyeshields, windshields or the like, and more particularly to a shield adapted for use in connection with a cap or other headgear.

The shield to which the present invention relates is primarily employed for the purpose of protecting the face of the wearer and especially the eyes from wind, glare, etc. The face shield is well adapted for various uses, as for example, in sports where a light compact shield is desired, and it is therefore adapted to be employed with a hat, cap, bandau or other article of headwear provided with visor. For convenience, the article of headwear is referred to hereinafter as a "cap," but it will be understood that this expression, unless otherwise qualified, comprehends any type of headwear suitable for the purposes herein described.

In accordance with an illustrative embodiment of the invention, a face shield is provided from transparent material, preferably of the type which will reduce eyestrain due to glare, and so shaped as to be adapted to overlie a predetermined portion of the face of the wearer. The shield is provided with means, preferably detachable for attaching it to the visor of the cap, which means permits the shield to be readily moved into "operative" position before the face of the wearer, or into "inoperative" position relatively flat against the underside of the visor.

The shield may, if desired, be provided with one or more portions in the nature of extensions adapted to protect portions of the face, in addition to those protected by the main portion of the shield, and these extensions are so constructed and attached to the main portion of the shield so that when the shield is moved into inoperative position against the visor the extensions do not project beyond the visor.

The eyeshield may be provided with means for attaching it to the cap in such manner that its position relative to the face of the wearer can be adjusted.

An object of the present invention is the provision of a shield adapted to be associated with the visor of a cap for movement between inoperative position lying against the visor and operative position before the face of the wearer, and which when in operative position is bowed or arched to conform somewhat with the shape of the face.

Another object of the invention is to provide a shield which can be readily detached from the cap when not in use.

Still another object of the invention is the pro-

vision of shield of such construction as to protect a substantial portion of the face of the wearer but which is adapted to be collapsed into a compact unit against the visor of the cap with which it is associated.

Still another object of this invention is the provision of a shield which can be readily adjusted between a plurality of positions relatively to the face of the wearer.

Various other features and advantages of the invention will be apparent from the following particular description and from an inspection of the accompanying drawings.

Although the novel features which are believed to be characteristic of this invention will be particularly pointed out in the claims appended hereto, the invention itself, as to its objects and advantages, and the manner in which it may be carried out, may be better understood by referring to the following description taken in connection with the accompanying drawings forming a part hereof, in which:

Fig. 1 is a side elevational view of a cap having a shield associated therewith in accordance with the teachings of the invention;

Fig. 2 is an enlarged, fragmentary, bottom plan view showing the visor portion of the cap of Fig. 1 and the shield associated therewith, the shield being shown in inoperative position against the visor;

Fig. 3 is a view similar to Fig. 2, only showing the shield in operative position;

Fig. 4 is a view similar to Fig. 3, only showing the shield in an alternative operative position, wherein it is spaced farther from the face of the wearer than it is in the position illustrated in Fig. 3;

Fig. 5 is a bottom plan view of the visor of the cap shown in Fig. 1, and illustrating particularly the arrangement of fastener elements thereon;

Fig. 6 is a plan view of the shield and illustrating particularly the arrangement of fastener elements thereon;

Fig. 7 is a front elevational and somewhat perspective view of another embodiment of the invention wherein the eyeshield is shown in operative position;

Fig. 8 is an enlarged fragmentary cross-sectional view taken along the line 8—8 of Fig. 7;

Fig. 9 is a plan view of the shield, showing one of the extensions in collapsed, inoperative position and another of the extensions in extended, operative position;

Fig. 10 is a fragmentary bottom plan view show-

ing the visor and associated shield with the shield in operative position; and

Fig. 11 is a view generally similar to Fig. 10 only showing the shield in inoperative position.

In the following description and in the claims, various details will be identified by specific names for convenience, but they are intended to be as generic in their application as the art will permit. Like reference characters denote like parts in the several figures of the drawings.

Referring now particularly to Figs. 1 to 6 of the drawings, and more particularly to Fig. 1, an article of headwear is provided which, as above stated, may comprise any suitable type of headgear, and which in the present illustrative embodiment is a cap 100 having a visor 101.

Associated with and preferably detachably connected to the cap 100 is a shield 102 formed of transparent, flexible sheet material, such as Celuloid or a synthetic plastic or the like, which preferably is of such a nature or color as to protect the eye against glare.

The shield 102 is formed with a generally straight rear edge 115 which may have a slight curvature or angularity as indicated in Figs. 2 and 6, with a forward edge 116 shaped to lie within the border of the visor 101, when the shield is in inoperative position, as illustrated in Fig. 2. The forward edge 116 preferably is provided with a suitably shaped notch or indentation 103 to permit the shield to straddle the nose of the wearer.

The shield 102 is detachably and hingedly connected to the visor 101 substantially on the fore and aft center line thereof, by a connection which comprises a flexible strap-like member 104, formed from leather, fabric or other suitable material permanently fixed to the shield as by a rivet 117, and carrying a male snap fastener element 105. A female snap fastener element 106 is secured to the visor 101 for cooperation with the male snap fastener element 105.

The shield 102 is provided at its lateral extremities with male snap fastener members 107 adapted to engage female snap fastener elements 108 secured to the visor near the sides thereof and slightly forward of the female fastener 106. When the male snap fastener elements 107 are engaged with the snap fastener elements 108 on the visor, the shield is thereby maintained in inoperative or "out-of-use" position, as illustrated in Fig. 2.

When it is desired to move the shield 102 into operative or "use" position, the male snap fastener elements 107 are disengaged from the female snap fastener elements 108 and the shield 102 is swung downwardly into position approximately at right angles to the visor. The shield 102 is provided with male snap fastener elements 110 connected to the shield by flexible straps 111 at the lateral extremities of the shield. The male snap fastener elements 110 engage female snap fastener elements 112 secured to the visor 101 rearwardly of the first set of female snap fastener elements 108, and so located that when the snap fastener elements 110 are engaged therewith, the shield 102 is bowed rearwardly as illustrated in Fig. 3. This operative position of the shield as above described, is illustrated in Fig. 3.

In certain cases, as for example, where the wearer is accustomed to wearing spectacles, it is desirable to place the shield 102 in operative position at somewhat greater distance from the face of the wearer than it is when in the position illustrated in Fig. 3. In this case, the shield 102 is

swung about the pivot provided by the cooperating central snap fastener elements 105 and 106. The male snap fastener elements 110 are then engaged with the female snap fastener elements 112 to maintain the shield in operative, rearwardly bowed condition. This condition is illustrated in Fig. 4.

It will be noted that when the shield is in the position illustrated in Fig. 3, the shield is disposed 10 rearwardly of the three connections which it has with the visor of the cap. On the other hand, when the shield is in the condition illustrated in Fig. 4, it is disposed forwardly of the three connections. Thus, it will be observed that in the 15 first case, the shield is substantially closer to the face of the wearer than in the second case.

For some purposes it may be found desirable 20 to render opaque the body of the shield and provide eye-windows directly in front of the eyes, all as will be readily understood without further illustration.

In certain cases it is desirable to afford protection 25 for a greater portion of the face than is afforded by a shield of the type illustrated in Figs. 1 to 6, and in such case there is provided a shield having a main or body portion and extensions which extend outwardly from and thereby increase the effective area of the body. The extensions are adapted to be collapsed relatively 30 to the body portion so that the entire shield does not extend beyond the visor of the cap with which it is associated. A second, and in some respects a preferred embodiment, of my invention contemplates the provision of such a shield having 35 extensions.

Referring now particularly to Figs. 7 to 11, inclusive, a shield is provided which is associated with a cap 200 of any suitable construction having a visor 201. The shield comprises a main 40 or body portion 202 formed in a manner generally similar to the shield illustrated in Figs. 1 to 6 hereof. The shield is provided with a flexible hinge 203 preferably attached permanently to the body 202 as by a rivet 204, and carrying at its 45 free end a female snap fastener element 205 adapted to cooperate with a male snap fastener element 206 secured to the visor 201. The shield thus can be detachably secured to the visor and can be moved between inoperative and either of 50 two operative positions in a manner generally similar to that above described.

Flexible members 210 are suitably secured to the lateral extremities of the body 202 as by female snap fastener elements 211, and the flexible members 210 carry female snap fastener elements 212 adapted to cooperate selectively with forward, male snap fastener elements 213 or rearward, male snap fastener elements 214 in a manner equivalent to that described above.

An extension 225 or wing is associated with each side portion of the body 202 and is secured to the body pivotally in a suitable manner 60 preferably by the corresponding snap fastener element 211. The extension 225 is adapted to be swung from inward inoperative position, wherein it is collapsed against the body 202 (as illustrated at the left hand side of Fig. 9), and outward, operative position standing away from the body (as illustrated at the right hand side of Fig. 9).

The extension 225 is of generally segmental 70 form and is provided with an outward edge 227 which preferably corresponds generally with the shape of the associated edge 223 of the body 202, and with an inward edge 228 which also conforms generally with the shape of the edge 223.

The extension 225 is provided with a slot 226 which receives a rivet or other member 221 fixed to the body 202 which guides the extension 225 between operative and inoperative positions, and prevents undesired displacement of the outer end of the extension 225. The slot 226 takes approximately the form of an arc with its center substantially at the pivot constituted by the rivet 211. Preferably, however, the inner end portion of the slot 226 is slightly closer to the pivot than is the outer end portion whereby, when the extension 225 is swung out to its operative position, the extension is bowed slightly and thereby conforms generally to the shape of the adjacent portion of the face of the wearer.

In certain cases, it may be desirable to provide protection for a greater portion of the nose and adjacent portion of the face of the wearer than is provided by the shield 202 above described. In this case, the lower edge of the shield is provided with an indentation 222 which does not extend inwardly as far as the indentation 103 of the shield 102. It is desirable therefore, that the lower edge of the body 202 be provided with means for protecting the nose of the wearer from abrasion, and in the present embodiment, this means comprises a soft strip 220 which may be formed from leather or other suitable material. The strip 220 preferably is secured to the body 202 by the rivets 221 which also serve as guides for the extensions 225.

The shield illustrated in Figs. 7 to 11 is used in a manner generally similar to the shield illustrated in Figs. 1 to 6 and is adapted to be moved into inoperative position against the visor as illustrated in Fig. 11, or to be moved into operative position depending from the visor as illustrated in Figs. 7, 8 and 10. When the shield is moved into operative position, the extensions 225 are drawn outwardly from the body 202 into the position illustrated particularly in Fig. 7 whereby the extensions protect portions of the face not protected by the body 202.

When it is desired to dispense with the use of the shield, the fastener elements 212 are detached from the fastener elements 214, and the shield swung upwardly against the visor and secured by engaging the fastener elements 211 with

the fastener elements 213. The extensions 225 are collapsed inwardly against the body into the position illustrated in Fig. 11 by rotating them about their respective pivots 211, 211, either before or after the shield is moved into inoperative position against the visor.

In the foregoing description, male and female fastener elements respectively have been referred to specifically as being provided at certain portions of the shield and visor respectively, but it will be understood that they may be reversed on the respectively cooperating members. Moreover, the invention is not limited to the employment of any particular type of readily detachable securing elements.

While certain novel features of the invention have been disclosed herein, and are pointed out in the annexed claims, it will be understood that various omissions, substitutions and changes may be made by those skilled in the art without departing from the spirit of the invention.

What is claimed is:

1. In a head gear, a cap having a head engaging portion and a visor, a shield having at least a portion thereof transparent, cooperating elements on said shield and on said visor whereby said shield may be secured selectively in a plurality of operative positions, said operative positions being in front of the eyes of the wearer but at different distances therefrom.

2. A cap comprising a visor, an eyeshield having at least a portion thereof transparent, said eyeshield being hingedly, pivotally and detachably secured to said visor, said visor having in the body thereof rear and forward snap fasteners on either side and a central snap fastener, said eyeshield having secured to its hinged edge flexible side straps and a central strap, said side straps and said central strap having snap fasteners for engagement with the side rear and the central fasteners on said visor, to hold said eyeshield in operative position, said eyeshield having on either side and in the body thereof adjacent its hinged edge snap fasteners adapted to engage the forward snap fasteners on said visor to hold said eyeshield in inoperative position against said visor.

WILLIAM F. SERR.
